DEVICE FOR PRODUCING ORNAMENTAL
AND DECORATIVE BUBBLE LIGHTING
EFFECTSJohn Petry, Bayside, Long Island, N. Y., assignor
to Raylite Electric Corp., Bronx, N. Y., a cor-
poration of New York

Application May 6, 1946, Serial No. 667,580

7 Claims. (Cl. 240—10)

1

This invention relates to the manufacture of devices of producing ornamental and decorative bubble lighting effects and more particularly is directed to the construction of such devices and the use of improved compounded bubbling solutions.

Among the objects of the invention is to generally improve devices and compounds of the character described which shall be easy, simple and economical to manufacture and adapt for quantity production so as to provide a cheap and inexpensive product, which shall be dependable and reliable in operation requiring a minimum of external heat supply, which shall be capable of giving a wide range of predetermined bubble lighting effects, which improved compounded solutions may be made non-inflammable, non-explosive and readily removable when spilled to eliminate permanent stains, and which shall be practical and efficient to a high degree in use.

Other objects accordingly consist of features of constructions, combinations of elements, arrangement of parts which will be exemplified in the constructions hereinafter described and of which the scope of the application will indicate in the following claims.

In the accompanying drawing in which possible illustrative embodiments of the invention are shown:

Fig. 1 is a front elevational view, partly broken away to expose the interior construction, showing a device for producing ornamental and decorative bubble lighting effects constructed to embody the invention and operating under substantially atmospheric pressure.

Fig. 2 is an enlarged fragmentary front elevational view of the bottom tube body and of the device shown in Fig. 1.

Fig. 3 is a fragmentary front elevational view similar to Fig. 1 showing the bubbling effect operating at less than atmospheric pressure, and

Fig. 4 is a fragmentary front elevational view similar to Fig. 1 showing a variation of bubbling effects by operating with a solution having a relatively greater proportion of readily volatilized constituent than that shown in Figs. 1 and 2.

Devices for producing ornamental and decorative bubble lighting effects heretofore available have been found to be deficient in reliability of operation, in being relatively expensive to manufacture and difficult to produce in quantity production to provide a cheap and inexpensive product, in liability to cause dangerous explosions, fires and permanent stains due to spillage of the bubbling solutions when tubes in which said so-

2

lutions are enclosed accidentally break, and in having limited range of unpredictable bubbling effects.

To overcome these deficiencies, as seen in the drawing, there is provided improved device 10 for producing ornamental and decorative bubble lighting effects suitable as Christmas tree ornaments, or for other display purposes, constructed to embody the invention. As shown in Fig. 1, said device 10 may include a vertically disposed transparent tube body made of glass or other translucent material designated as 11, having an integral closed lower or bottom flat end 11a and a sealed top end 11b. Said body portion 11, when the device 10 is intended, as here, to be used as a Christmas tree decoration, is made in appearance, such as contour and size, to simulate a candle.

In the forms of the invention shown in the drawing, the tube body contains a translucent liquid 12, comprising an improved compounded bubbling solution of a character hereinafter described. Said liquid may be placed into the tube body 11 through the upper or top end 11b thereof before fusing or closing the latter for hermetically sealing the liquid 12 therein at a level so as to leave an adequate condensing chamber or space 13 in the tube end 11b. As shown in Figs. 1 and 2, said sealed space 13 may be left under substantially atmospheric pressure, and constitutes a heat dissipating means for liquefaction of large bubbles 15 and small ones 15a rising in the liquid 12 to the upper level thereof.

There may also be provided a flat disc or wafer 16, preferably firmly fitted or seated in fixed position to substantially cover the lower end of the tube body 11 and abutting against the inner surface of the tube end 11a, said disc 16 preferably being made of a suitable porous surfaced material such as cork, to serve as a bubble generating activator or stimulator. Said disc 16 may also be made of glass which like cork has relatively high heat insulating properties that are effective to equalize and retain the heat transmitting conditions for smooth and prolonged bubble generation in the operation of the improved device 10. Said disc or wafer 16 may have spaced peripheral through passages 16a provided which appear to serve as focal points for initiating bubble generation.

For supplying operating heat and light to device 10 any suitable radiant heat source may be provided. For example, as shown in Fig. 1, the tube 11 is supported with the lower or bottom end 11a thereof located in close proximity

to lamp bulb 20a of an incandescent lamp 20, the latter being mounted in an electric socket 21 of conventional construction to form part of a Christmas tree lighting outfit or other display or decorative (not shown) in the well understood manner.

A sleeve holder or connector 22 is fitted snugly over the lower or bottom tube end 11a and the lamp bulb 20a to provide a firm interconnecting support or rigid coupling for mounting the device 10 in position. Said holder 22 may be made of fibre, glass, plastics or other non-combustible material and serves as a conduit to guide the air surrounding the lamp bulb 20a with the glowing filament 20b as a heat conducting medium to the tube bottom end 11a.

The use of the improved compounded bubbling solution forming liquid 12 which comprises a plurality of constituents of different physical characteristics is one feature of the invention. While it has been generally recognized that bubbling devices of the character described could be made and operated using readily volatilizable liquids of relatively low viscosity, as for example, ether, wood alcohol, methylene chloride, methanol and the like, such prior volatile liquids have been found deficient and undesirable in practical use for one or more reasons given above. It has also been found that it is difficult to predict within reasonable and practical accuracy the bubbling performance effects to be expected using such prior liquids in commercial manufactured devices. It is proposed herein to use instead of said prior volatile liquids, improved solutions each comprising principally of at least two constituents having such reverse type of character, as for example, an oil like constituent of relatively high viscosity which at operating temperature is relatively non-volatile and a readily volatilizable constituent of relatively low viscosity, such as methylene chloride, chloroform or ether and the like. While various products of mineral, animal, vegetable and synthetic origin may be used as the relatively non-volatile and high viscous constituent, organic oils such as inexpensive rape seed, castor or cod liver oils and the like have been found to give satisfactory results in making solutions with one of said readily volatilizable constituent in providing the improved solution liquid 12. The amount of such volatilizable constituent in the solution of liquid 12 may be varied greatly to give various bubbling effects. Though such volatilizable constituent alone may be flammable, in solution the oil like constituent serves as a fire retardant. Where the volatilizable constituent is flammable, a relatively small amount of carbontetrachloride which is also readily volatilizable, may be included in the solution liquid to insure against fire and explosion hazards.

Liquid synthetic resins, containing polystyrene or vinyl plastics (such as commonly known as "Lucite") may also be used in solution liquid 12 if desired as the oil like viscous and non-volatile constituent, the latter being soluble in methylene chloride may be added thereto in granular form when providing said liquid 12.

By using organic oils instead of those of synthetic origin, such as lacquers, liquid synthetic resins and the like, stains that may be accidentally caused by spillage in breaking of the tube 11 are more readily removed.

In practicing the invention, assuming the socket 21 forms part of a Christmas tree or other decorative display, and is connected in an electric circuit (not shown) for lighting lamp 20 in

the well understood manner, heat radiating from the lamp filament 20b is effective to heat the tube end 11a and the cork or glass disc 16 therein. The lower end of the column of solution liquid 12 is heated by contacting said disc 16 and the readily volatile and low viscous constituent thereof is vaporized therefrom. Said peripheral grooves 16a serve as focal points of the bubble generation to form bubbles 15 and 15a rising through liquid column 12, the latter being under substantially atmospheric pressure as shown in Figs. 1 and 2. The sleeve holder 22 serves as a conduit to effectively confine the heat conducting medium, namely, air, therein.

Thus there is provided the degree of heat necessary from a minimum heat source at lamp filament 20b, sufficient light beams from bulb 20 being projected either through the glass disc 16, or when disc 16 is made of cork through the side walls of the transparent tube body 11 to illuminate the liquid column 12 and bubbles 15 and 15a thereby producing an attractive activated novel bubble lighting effect. By using colored glass discs 16 various desired colors may be produced in liquid 12 and bubbles 15 and 15a.

The column of solution liquid 12 within the tube body 11, which when said device 10 is operating, extends between the cork or glass disc 16 and the top tube space 13, and may be under atmospheric pressure condition in the top space 13, as shown in Figs. 1 and 2. Said solution liquid 12 has external illuminating radiant heat applied thereto, as by means of the glowing lamp filament 20b which is positioned to maintain the disc 16 heated and supplied to an effective degree sufficient to volatilize the low viscosity constituent, or constituents when carbontetrachloride is included, of the solution liquid 12 contacting the cork or glass disc 16 and at the focal points provided at the peripheral slots 16a dissociating the same from the solution to form bubbles 15 and 15a which float up through the length of said liquid column 12. The high viscous constituent provides a float support medium of substantial buoyancy in the liquid 12 for said bubbles 15 and 15a. Under certain effective conditions such as providing substantially atmospheric pressure in tube space 13 many minute bubbles 15a will also be formed which slowly rise and simulate a background for a stream of individual relatively more rapidly rising larger bubbles 15. The flowing bubbles 15 and 15a rising through liquid column 12 produced are illuminated by light beams emanating from the lamp filaments 20b as shown in Figs. 1 and 2.

The bubbles 15 and 15a on reaching said top space 13 after passing through said liquid column 12 are cooled, condensed and liquified, and flow down into the solution liquid 12 for replenishing and restoring the relative constituent solution composition to repeat the cycle of operation above described. Said bubbling action continues as long as there exists a sufficient heat gradient or differential temperature between the vapor in bubbles 15 and 15a at said disc 16 and the condensation in top space 13 after liquefaction of said bubbles 15 and 15a, that is as long as vapor pressure at bottom of liquid column 12 at disc 16 exceeds the vapor tension in said space 13.

After the lamp 22 is lighted, self-starting of the bubbling operation of device 10, takes place on the heated surface of disc 16 and in one or more of the peripheral slots 16a, the heating of non-volatilized oil constituent of solution liquid 12

appears to favor such action. The surrounding oil constituent of relatively high viscosity left, when said low viscous bubble forming constituent or constituents volatilize from solution liquid 12, serve as a viscous drag to retard bubble movement and aid in building up the larger individual bubbles 15 which form a stream moving up through the solution liquid 12 slower than otherwise would be the case.

In the above construction and operation, no static condition is experienced and self-starting of the bubbling operation eliminates all necessity of jarring the tube after turning on the heat thus providing a more practical device of the character described than those of the prior art.

Further advantage of using a solution liquid 12 comprising high and low viscous constituents is that the range of bubbling effects can be greatly varied particularly when different pressures are provided in tube space 13. Thus by varying the quantities of high and low viscous constituents making up the solution liquid 12 and providing relatively a high, intermediate, or low pressure in space 13, a great variety of bubbling effects are produced each of which can be predetermined by reproducing the solution liquid 12 of the same constituents and providing the same pressure in space 13 of the device 10. In Fig. 3, for example, there is shown the effects of simply providing a reduced pressure in tube space 13 instead of atmospheric pressure to permit lowering the boiling point normally required for the constituents in liquid 12 but retaining the same liquid 12 as in Figs. 1 and 2. The bubbles 15 are accelerated in movement through the liquid 12 and said bubbles 15 appear in greater quantity and more uniform in size. The top 12a of the liquid column 12 also appears frothy in this operation.

In Fig. 4 there is shown another modified form of the invention effective by merely varying the proportions of the relatively readily volatilizable and low viscous constituent with relation to the relative viscosity of the liquid 12 so that the amount of volatilizable constituent used is much greater compared with that producing the effects shown in Figs. 1 and 2 and described above. The bubbling effect in Fig. 4 appears as continuously winding stream flows 115 intermingled with small floating bubbles 15a in liquid 12 and is headed in space 13 by a bubbling froth 12a. Various other different bubble effects can be produced by using other solutions of liquid 12 comprising various different proportions and kinds of said constituents and operating under different pressures in space 13.

All of the above effects can be predetermined, after once produced, by duplicating the kinds and proportions of constituents making up the solution 12 and by operating under the same pressure conditions in space 13.

It is, therefore, seen that there is provided improved devices and solution liquids in which the objects of the invention are achieved and which are well adapted to meet all conditions of practical use.

As various possible embodiments may be made

in the above invention for use for different purposes and various changes might be made in the embodiments above set forth, it is understood that all the above matters here set forth, or shown in the accompanying drawing are to be interpreted as illustrative and not in a limiting sense.

Thus having described my invention, I claim as new and desire to secure by Letters Patent:

- 10 1. A bubbling device of the character described comprising a sealed transparent elongated tube body, a solution liquid compounded of a plurality of constituents in said tube body, a holder for supporting an end of said tube body with the solution liquid, means in said holder for applying heat externally to said tube body end, one of said constituents having high volatility and low viscosity, the other of said constituents having low volatility and high viscosity so that said first constituent is more volatile and less viscous than the said second constituent, whereby on the application of said heating means the first constituent is dissociated from said solution and volatilized to produce a flowing stream of bubbles in said liquid.
- 15 2. A bubbling device of the character described having a transparent tubular body, a solution comprising a plurality of liquid constituents sealed in the body, at least two of said constituents having reversed characteristics as to volatilization and viscosity, one of said constituents having high volatility and low viscosity, the other of said constituents having low volatility and high viscosity for producing on heating dissociation and vaporization of the high volatile constituent to form a flowing bubble stream in said liquid, the relative proportions of said constituents being selected to attain a characteristic bubbling effect.
- 20 3. A bubbling device of the character described having a transparent tube body with sealed-in bubble forming solution liquid comprising a plurality of constituents, one constituent having relatively low viscous and highly volatilizable characteristics, and another constituent having relatively high viscous and low volatilizable characteristics, said first mentioned constituent being vaporizable on application of heat to the solution liquid in said tube body to dissociate same and form flowing bubbles therein.
- 25 4. The bubbling device as defined in claim 3 in which vaporization of said low viscous and highly volatilizable constituent is effective under substantially atmospheric pressure.
- 30 5. The bubbling device as defined in claim 3 in which vaporization of said low viscous and highly volatilizable constituent is effective under pressure less than atmospheric.
- 35 6. The bubbling device as defined in claim 1 having bubble stimulating means positioned in said tube body end to facilitate initiating bubbling operation on the application of heat.
- 40 7. The bubbling device as defined in claim 2 including bubble initiating means in said tube body to facilitate self-starting generation of the flowing bubbles on said application of heat.

JOHN PETRY.
